UNITED STATES PATENT OFFICE.

EDWARD THIMGREN, OF POPOTLA, MEXICO.

CIGARETTE CASE.

Application filed December 28, 1922. Serial No. 609,508.

To all whom it may concern:

Be it known that I, EDWARD THIMGREN, a subject of the King of Sweden, residing at Popotla, Distrito Federal, Mexico, have invented certain new and useful Improvements in Cigarette Cases, of which the following is a specification.

This invention relates to new and useful improvements in pocket cigarette cases of the type adapted for successively dispensing its contents.

An important object of the invention is the provision of a case of the type above set forth wherein the cigarettes may be discharged successively as desired by the user without opening the case.

A further object of the invention is to so construct a cigarette dispensing case that its contents may be safely stored therein without danger of being mutilated by the ejecting mechanism mounted within the case.

Other objects and advantages of the invention will be apparent during the course of the following description.

In the accompanying drawings forming a part of this present case and in which like numerals are employed to designate like parts throughout the same,

Figure 1 is a sectional view of a cigarette case embodying my invention,

Figure 2 is a vertical sectional view taken on line II—II of Fig. 1,

Figure 3 is a vertical sectional view taken on line III—III of Fig. 1,

Figure 4 is a horizontal sectional view taken on line IV—IV of Fig. 1,

Figure 5 is a fragmentary sectional view showing in detail the cigarette discharging plunger,

Figure 6 is a vertical sectional view taken on line VI—VI of Fig. 5,

Figure 7 is a fragmentary sectional view showing the discharging plunger in its extended position.

Referring more in detail to the accompanying drawings, there is illustrated a cigarette case, which is preferably constructed of metal, but may be constructed of any other suitable material, and embodies an open face commodity containing compartment 1 and a closed compartment that is positioned externally of the commodity compartment. Both compartments are provided with a rear wall 3, upper wall 4, and

side wall 5, while the commodity compartment is further provided with a side wall 6 and lower wall 7, the side wall 6 and lower wall 7 forming a partition between the two compartments. The upper and lower walls 60 of the commodity compartment are provided with openings 8 and 9 respectively, the use of which will be apparent from the description to follow. The closed compartment 2 is further provided with a side wall 65 10, front wall 11, and lower wall 12. The open face of the commodity compartment 1 allows for the placing of cigarettes within the compartment and is provided with a door 13 connected to the front wall 11 by 70 the hinges 14, the door is further provided with a clasp 15 for retaining it in a closed position when the device is in use.

Arranged within the commodity compartment 1 is a follower plate 16 having 75 guide straps 17 adapted to slidably engage the strap springs 18 that are secured to the upper wall 4 and lower wall 7 as shown. The follower plate, when the commodity compartment has been filled, resumed a position as shown in Fig. 1 and forces the innermost cigarette 19 transversely through the compartment toward the side wall 5, bringing one of the cigarettes directly in line with the openings 8 and 9 in readiness for being 80 ejected. The strap springs 18, due to their tendency to lie flatly against the walls 4 and 7, will continue to urge the cigarettes forward until the upturned ends 20 of the strap springs 18 engage the guide strap 17 85 and prevent further movement. It will be apparent that the upturned ends 20 will follow their respective arcs as shown in dotted lines in Fig. 1 and will continue to force the follower plate forward until the 90 innermost cigarette 19 is in line with the openings 8 and 9. The cigarette lying adjacent the side wall 5 is ejected through the opening 8 by the upward movement of the cup-shaped plunger 21 through the opening 9. The movement of the cup-shaped plunger is manually controlled by the push button 22 that projects through the opening 23 in the side wall 10, an annular shoulder 24 being provided on the push button to 105 prevent outward displacement therefrom.

Formed integrally with the side walls 10 are a pair of spaced lugs 25 which act as a support for the lever 26 pivotally connected thereto by the pin 27, the said lever having 110

a straight leg 28 which freely engages the inner end of the push button 22 and a leg 29 provided with a curved end 30.

Pivotedly mounted as at 31 to the spaced lugs 32, formed integrally with the lower wall 12, is an angular lever 33 having a leg 34 provided with a bifurcated end 35 and a leg 36 provided with an upturned end 37 which freely engages the convexed side of the curved end 30 carried by the lever 26. Secured to the lower wall 12 and positioned in alinement with the opening 9 is a guide post 38 having a flat upper end 39 which provides a rest for the spiral spring 40. The plunger 21 being of inverted cup-shape to provide a recess for receiving the upper end of a spiral spring 40, carries a pair of depending arms 41 adapted to slidably engage opposite sides of the guide post 38. Secured to the lower ends of the depending arms 41 are knobs or lugs 42 which freely engage the lower face of the bifurcated end 35 for operatively connecting the plunger with the angular lever 33. Secured to the side wall 6, as by rivets 43, is the leaf spring 44 which freely engages the lever leg 28. It is to be understood that the leaf spring 44 is sufficiently strong to retain the ejecting mechanism in its full line position as shown in Fig. 1, against the action of the spiral spring 40.

When it is desired to eject a cigarette from the case, the push button 22 is pressed inwardly to move the lever 26 into the dotted line position, as shown in Fig. 1, against the pressure of the leaf spring 44. The movement of the lever 26 will free the lever 33 for allowing the spiral spring 40 to force the plunger 21 upwardly through the opening 9 to eject a cigarette through the opening 8. Upon removing the pressure from the push button 22, the leaf spring 44 will return the lever 26 to its normal position, the curved end 30 of the lever 26 will press against the upturned end 37 of the lever 33 for rocking the same upon its pivot pin 31 to draw the plunger downwardly against the pressure of the spiral spring 40 thus returning the plunger 21 to its inoperative position.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In a device of the type described, a commodity containing compartment having openings, means positioned within said compartment for moving its contents successively into alinement with said openings, a

second compartment carried externally of the first mentioned compartment extending along two side walls of the same, a resiliently mounted plunger located at the end of one wing of the second compartment in alinement with said openings, an angular lever pivotally mounted in said wing operatively connected to said plunger and projecting into the other wing of said second compartment, a lever pivotally mounted in the last mentioned wing operatively engaging the angular lever, resilient means engaging the last mentioned lever for normally retaining the plunger in its inoperative position, and means for actuating the last mentioned lever to cause the plunger to eject the portion of the contents in alinement with said openings from the commodity compartment.

2. The combination with a commodity containing compartment having alined openings formed in its upper and lower walls in juxtaposition to one end wall, a follower plate having guide straps positioned within said compartment extending at right angles to said upper and lower walls, and a strap spring secured at one end flatly against each of the upper and lower walls adjacent the other end wall with the remaining portions slidably engaging the guide straps for causing the follower plate to move transversely through the compartment due to the tendency of the springs to assume their normal positions flatly against the upper and lower walls for successively feeding the commodity into alinement with the openings, of a second compartment secured to the first exteriorly on two sides thereof, and means positioned within the second compartment for ejecting the commodity that has been moved into alinement with said openings.

3. In a device of the type described, a commodity containing compartment having openings, means positioned within said compartment for moving its contents successively into alinement with said openings, a second compartment carried externally of the first mentioned compartment extending along two side walls of the same, a guide post positioned within the second compartment at the end of one wing in alinement with said openings, a plunger having depending arms associated with the guide post, resilient means positioned between said post and plunger, an angular lever pivotally mounted in said wing operatively connected to the depending arms carried by said plunger and projecting into the other wing of said second compartment, a lever pivotally mounted in the last mentioned wing operatively engaging the angular lever, resilient means engaging the last mentioned lever for normally retaining the plunger in its inoperative position, and means for actuating the last mentioned lever to cause the plunger to eject the portion of the contents in alinement with said openings.

alinement with said openings from the commodity compartment.

4. In a device of the type described, a commodity containing compartment having openings, means positioned within said compartment for moving its contents successively into alinement with said openings, a second compartment carried externally of the first mentioned compartment extending along two side walls of the same, a guide post positioned within the second compartment at the end of one wing in alinement with said openings, an inverted cup-shaped plunger having depending arms associated with the guide post, resilient means positioned between said post and plunger, and an angular lever pivotally mounted in said wing operatively connected to the depending arms carried by said plunger and projecting
- into the other wing of said second compartment, a lever pivotally mounted in the last mentioned wing slidably engaging the projecting portion of the angular lever, a leaf spring engaging the last mentioned lever for normally retaining the plunger in its inoperative position, and a push button projecting from the second compartment for actuating the last mentioned lever to cause the plunger to eject the portion of the contents in alinement with said openings from the commodity compartment. 20
